PATTERN TRANSFER PRINTING ELEMENTS
Gregory R. Lynch, Burlington, and Joseph F. Tuscher,
Reading, Mass., assignors to The Carter's Ink Com-
pany, Cambridge, Mass., a corporation of Massachusetts
Filed Apr. 12, 1961, Ser. No. 102,555
2 Claims. (Cl. 101—149.4)

This invention relates to printing and more particularly to the printing of patterns, designs, and outlines for decorative or patterning purposes, or other uses where a design or outline is to be applied on a base surface. The invention consists of a sheet having the desired pattern printed on one side by means of a readily transferable material, and thus provides a convenient and inexpensive means for marking fabrics or construction materials in dressmaking and home crafts, or for applying a decoration or other marking to fixed surfaces, such as in decorating windows and walls.

Present techniques for transferring a design or pattern from a print to a work surface include various reproduction and drafting methods, free hand work, the direct attachment of a thin pattern or template, all of which possess disadvantages such as expense, lack of precision, or in requiring fine skills. Proposals have been made to print a design or pattern on a base sheet which can be laid over the workpiece, and a marking made by applying pressure over the design. According to U.S. Patent No. 482,451, a pattern formed of printer's ink mixed with wax and applied to a paper base may be transferred by pressing a stylus along the lines of the design. A similar result may be obtained by tracing a design with a soft pencil on tracing paper, and then retracing on the opposite side with sufficient pressure to mark an underlying surface. A practical difficulty lies in the pressure applied from a stylus, which, although only a few ounces of total force comes to a unit pressure which is so very high as to be unsuitable under many conditions. Where the workpiece is fabric, it tends to shift in following the stylus, and its soft working surface will yield, causing the paper base to puncture or wrinkle.

Other similar products are described by Maddock, U.S. Patents Nos. 2,228,280 and 2,233,791 and Kneale, U.S. Patent No. 2,408,147, the former employing a cellulose acetate film base, and the latter a wax impregnated paper base. All require a stylus pressure to effect a transfer and are accordingly not well suited for use on soft surfaces, or under conditions where high unit pressures are to be avoided.

The transfer sheets of this invention utilize a paper base which carries an outlined pattern of a readily transferred marking material by which a pattern, outline, or design may be printed under very light pressures, such as that attained by rubbing the sheet with a teaspoon or the heel of the hand. In the development of such a product, many problems were encountered which suggested that a sheet of the type sought could not be produced. Transferable marking materials which adhere well to the base do not transfer well under light pressures, while those that are soft enough to transfer easily generally lack decent adhesive properties. Greater difficulties are encountered where a reusable sheet is to be provided for the necessary increased thickness of transferable material tends to result in excessive smudging with soft materials whereas harder materials tend to chip from the base. Experiments with various types of paper indicate that some of the difficulties could be avoided by employing a paper of higher porosity. That however resulted in a base of greatly reduced transparency which could not be sacrificed because of the need of seeing the underlying surface for proper pattern positioning. Although high

2

transparency and high porosity are contradictory properties, a combination of a paper base composition and readily transferable material was found which would yield the desired product. The transfer material is a relatively soft yet coherent waxy composition containing coloring or pigment, of a type commonly employed in "carbon paper." Not all carbon paper dopes, however, are suitable, as some are too soft and smudge easily while others are too hard and do not transfer under the low pressures required for this product.

Adherence and transfer properties were attained by the discovery of a composite paper structure which combined strength, weight, transparency, and porosity in a single sheet. A paper was formulated for use in the sheet of this invention, having a porous fibrous side to which the transfer material would adhere, while being more highly compacted and translucent at the opposite side and inwardly through a sufficient fraction of the thickness that over-all translucency is provided.

The wax transfer material may therefore be applied so as to penetrate substantially into the body of the sheet and also to extend substantially from the surface of the sheet, being in the nature of a block printing character securely anchored physically within the fibers at the printed surface. The waxy transfer material is thus firmly secured physically to the sheet without requiring inherent adhesive properties, and may be formulated to possess those properties giving good transfer under conditions of use.

The backing sheet of this invention may accordingly be characterized as a paper base having its fibers relatively loosely compacted at one surface to provide for penetration of the transfer material (applied in the liquid state) but being over-all more densely compacted and translucent. The degree of compactness may roughly be set forth on the basis of paraffin penetration values, and air resistance values while the over-all transparency can be related to density and weight.

Suitable papers have been found to have the following characteristics:

Ream weight, 20-35 lbs. (500 sheets 24" x 36")

TAPPI *: T-410-M-45

Porosity (air resistance), 20-35 seconds, TAPPI *:
T-460-M-49

Paraffin absorption, over 15, TAPPI *: T-467-M-48

The relative compactness of the opposite surfaces may be provided by machine glazing the paper, whereby one surface is calendered or pressed to a more dense condition while the fibers of the opposite surface (the felt side) remain loose and more distantly spaced. Alternatively, two separate paper furnishes may be employed, first one of stock yielding a transparent sheet, e.g. well beaten relatively long fibers, followed by an over-coating from a secondary head box of less well beaten fibers yielding a more porous base. Numerous other ways may also occur to those skilled in the paper making art, by way of proper selection of paper stock, fiber length and type, degree of beating, degree of cutting, provision of fillers, binders, etc., all of which have definite effects which may be utilized selectively to produce the desired result. It is accordingly contemplated that a paper maker, given specifications as to the type of paper required, may readily produce it without so much experimentation as to amount to invention. The present disclosure confirms that an essentially translucent, relatively heavy weight paper may be made having one surface loosely compacted and of relatively high porosity (these intrinsically lacking in transparency) without destroying

the over-all transparency of the sheet as a whole. It is contemplated that a paper maker familiar with the disclosure will be able to produce paper suitable for this invention by several methods and different types of materials.

Transfer materials suitable for this invention are in general wax base formulations having a precision penetrometer reading in excess of about 0.25 mm. (as measured by a precision penetrometer) and transferable to give a visible trace by a rolling pressure of about 100 grams applied through a one-half inch hard sphere to the back of the transfer sheet faced to a bond paper sheet supported on a hard surface (e.g. glass or marble). Formulations meeting these characteristics are known in the carbon paper trade, and may be selected on the basis of the criteria herein set forth.

The manufacture of the printing element of this invention requires a process by which a waxy material may be applied in a layer of substantial thickness, with relatively deep penetration of part of the material into the paper base, with the remainder projecting from the printed surface. It was found that an intaglio printing process could be employed which made use of a high capacity deeply etched print roller coupled with temperature control of the roller and of the paper web both before and after printing. The printing roller is etched to provide for the application of a layer one to two mils in thickness and is heated to slightly above the melting point of the transfer material. The paper is fed to the printing roller after being preliminarily heated from a proximate hot box, so that solidification of the waxy material does not result upon contact, and is then passed close to a second hot plate suitable to maintain the transfer material liquid to assure adequate penetration. The degree of heating provided by the second hot plate is controlled to give the desired penetration of transfer material. Following this step the paper is passed close by a chilled plate to cause the transfer material to harden before the sheet is rewound.

Pattern transfer printing elements of this invention enjoy such a variety of uses as printing decorations, patterns, advertising material and the like on a suitable base surface, laying out of patterns for such varied purposes as dressmaking, boat building, general ornamental outlines for woodworking or metal working, and any application where an outline or design is to be provided on an underlying surface. The sheet is simply laid over the surface and positioned to the desired location, and then a light rubbing pressure from the hand or from a smooth rounded object, such as the back of a tablespoon, is applied. Where several prints are to be made, the paper may then be shifted to the next location and the process repeated. The outline then provided on the underlying surface may be used to guide further decoration, or to mark the material for cutting.

The transfer materials are generally those formed from a waxy base, which will generally include a wax or wax-like material together with greases and oils or other compatible materials providing suitable hardness and transfer properties, and a pigment or dye or other marking material, the presence of which will render the pattern or outline visible or otherwise discernable. Formulations of this type, having the requisite hardness and transferability, are known and may be formulated by those skilled in the carbon paper art. The invention is not limited to particular formulations other than as they may be set forth with reference to those physical properties which are significant to the product herein described.

The invention is set forth in greater detail below with reference to the accompanying drawings which are purely schematic and probably very greatly exaggerated representations of the various aspects of the invention.

FIG. 1 is a visualized and undoubtedly idealized representation of a greatly enlarged cross section of a fragment of the sheet of this invention;

FIG. 2 is a plan view showing a simple doll's dress pattern which may be considered representative of the utility of this invention;

FIG. 3 illustrates the method of transferring the pattern from the sheet of FIG. 2 to an underlying fabric; and

FIG. 4 is a schematic representation of the gravure process of the sheets of this invention.

FIG. 1 illustrates schematically the physical characteristics of the base sheet 10 and the bonding of the transfer material 12. The base sheet 10 is a relatively heavy paper, in comparison with papers ordinarily used in carbon paper, in which suitable transparency combined with sufficient porosity to hold the transfer material is provided by forming the paper with relatively densely compacted fibers inwardly from the top surface, and with relatively loosely compacted fibers at the bottom surface. The transfer material 12 is applied to penetrate into the loosely compacted fibers and is thereby securely anchored to the sheet 10.

In the preferred embodiment of the invention, the base sheet 10 is a 28 pound (per ream of 500 sheets 24" x 36") chemical pulp paper, machine glazed on the wire side only. Machine glazing is carried out by drying the paper from a partially wet condition with the wire side against a polished heated steel drum, e.g. on a Yankee drier. As a result the fibers at the wire side become relatively densely compacted. The felt side is unglazed and the fibers there remain loosely compacted while the paper on the whole is highly translucent.

Significant properties are as follows:

Thickness	-----	About .0023 inch.
Porosity	-----	Average 30 seconds.
Paraffin absorption	-----	About 32.
Optical density—det'd on Cary Spectrophotometer standardized on air	-----	2.7.

The transfer material 12 may be any of the known waxy carbon paper dopes which are soft enough to transfer under light rubbing pressures. For test purposes it has been found that suitable dopes, applied to a 15 pound (500 x 24 x 36) carbonizing tissue at a coating weight of 10 pounds per ream, will transfer to an underlying paper sheet supported on a hard (glass) surface under a load of 100 grams applied by rolling a loaded hard (steel) ball one-half inch in diameter over the coated tissue. Dopes that do not transfer under that pressure are too hard for use in this invention. Suitably soft dopes have also been found to have a penetrometer value (as determined by test measurements made in accordance with ASTM Procedure D-217-52T with 150-gram load on the cone on samples prepared in accordance with ASTM Procedure D-1321-57T) in excess of 0.25 mm.

In one preferred embodiment the dope consisted of:

In parts by weight)

Wax:

Beeswax	-----	7
Carnauba	-----	19

—

26

—

Softener: Petrolatum	-----	34

—

Color:	-----	—

Oil soluble dyes	-----	2

—

Pigment	-----	38

—

Dispersing agent: soy bean lecithin	-----	0.4

—

The ingredients are combined by melting the wax and softener together and then adding the coloring material

while mixing and grinding thoroughly. The dope is applied as a hot melt at about 180° F. or higher.

The manufacture of the printing elements features the application of a relatively large amount of dope to the base sheet under conditions which assure adequate bonding. This is accomplished by an intaglio printing process employing an engraved print roll 24 in which the desired pattern is deeply etched to provide for an application of dope of at least one mil. Typically the engraving will be based on a half-tone screen of 40 cells per inch separated by a wall thickness of 50 μ , 100-150 μ in depth.

The roll is heated to apply the dope in its molten condition and the paper is heated to maintain the dope melted during and after application. As illustrated schematically in FIG. 4, the paper base sheet 10 is passed from a feed roll 28, over a hot plate 22, and then between the print roll 24 and an impression cylinder 26. The print roll 24 revolves with its lower portion in a trough 23 of molten dope, the excess of which is removed by means of a doctor blade 30. A pattern of dope corresponding to the engraving on the print roll is thereby applied to the paper 10. The paper 10 next feeds over a second hot plate 32, which keeps the dope molten sufficiently long for proper penetration, then passes over a chill plate 34 to harden the dope, and is finally wound on a take-up roll 36.

Typically the print roll 24 and hot plates 22 and 32 are heated by steam at 5 pounds p.s.i.g. and the chill plate 34 is cooled by water at about 52° F.

A pattern transfer printing element 40 bearing a doll's dress pattern is shown in FIG. 2, and in FIG. 3 is shown its manner of use, wherein the element 40 is laid over a fabric 41 and transfer is effected by rubbing the back (top) of the element lightly with a spoon 42. As many as 20-30 prints can be made in this manner.

A printing element formed in the manner described above will have a pattern of dope of a total thickness of about 1 to 2 mils, of which about half (0.5-1 mils) is penetrated into the backing sheet and the remainder projects from the surface. This application is significantly heavier than encountered in the manufacture of ordinary carbon papers, and the product as a whole also differs from ordinary carbon papers in that the dope backing sheet is much heavier, while still being translucent, and of suitably high porosity at the doped surface.

Although this invention has been described with reference to one preferred embodiment, numerous modifications respecting the exact types of paper and dope to be used will occur to those skilled in the art and familiar

with this disclosure, and such may be made without departing from the scope of this invention. In particular, dopes will be formulated with varying degrees of hardness or softness within the criteria herein set forth, for specific uses. Where patterns are to be transferred to a hard surface, such as glass, a softer dope is better than a harder one.

Variations in the paper backing sheet may also be made as long as the requisite properties of translucency, stiffness, and porosity are maintained.

Having thus disclosed my invention and described in detail a preferred embodiment thereof, I claim and desire to secure by Letters Patent:

1. A printing element in the form of a paper sheet 15 base carrying on one side an outlined pattern of waxy marking material transferable to an underlying surface under a pressure of 100 grams applied by a sphere one-half inch in diameter to the opposite side of said sheet, said sheet being a translucent paper of 20-35 pounds per 20 ream of 500 sheets 24" x 36", having a porosity of 20-30 seconds and a paraffin absorption in excess of 15, said marking material being a waxy carbon dope having a penetrometer value greater than 0.25 mm., and applied to a thickness of 1.0-2.0 mils with at least 0.5 mils penetrating into the surface of said sheet.

2. A printing element in the form of a paper sheet 30 base carrying on one side an outlined pattern of waxy marking material transferable to an underlying surface under a pressure of 100 grams applied by a sphere one-half inch in diameter to the opposite side of said sheet, said paper sheet being translucent and having fibers relatively loosely compacted on said one side, and relatively densely compacted on said opposite side, with part of said transferable material penetrating partially into the 35 sheet and embedding fibers at said one side without being present at said other side, part of said transferable material also lying outwardly from said one side to form a print contact portion raised at least 0.5 mil from the surface of said sheet.
